AUXILIARY TRAFFIC CONTROLLERS

Frank W. Hill, Moline, Ill., assignor, by mesne assignments, to E. W. Bliss Company, Canton, Ohio, a corporation of Delaware

Filed Apr. 10, 1959, Ser. No. 805,494

1 Claim. (Cl. 340—44)

This invention relates to auxiliary apparatus suitable for use in connection with an intersection traffic signal controller and adapted to add into the normal traffic signal cycle one or more pedestrian or traffic moving intervals after pedestrian or vehicle detector actuation. The normal traffic signal cycle may be timed by a standard intersection traffic signal controller. The auxiliary apparatus is connected into the terminal facilities associated with the intersection controller and has a controlling influence over the intersection controller. The accessory controls and times its intervals electronically.

It is well known to control the indication and duration of a plurality of traffic signal lights at an intersection through one cycle of operation under certain conditions of traffic and through a different cycle of operation following the actuation of a traffic detector. The above operation requires a two or three phase traffic controller designed specifically for such application.

What is believed to be new is to provide an electronic control and timer accessory which is able to insert an additional phase movement upon pedestrian or vehicle actuation thus enabling an existing controller to produce an additional phase for most efficient traffic movement.

A large number of traffic controllers in use today have an operating sequence limiting them to use on a two or three street intersection. The invention provides auxiliary means to add a pedestrian or vehicle actuated phase to an existing two or three phase controller.

A phase is here defined as one traffic movement and normally includes a "go" interval and a "caution" interval to traffic on one street. An interval is defined as one timed portion of the traffic signal cycle. Normally, one interval is given over to each different signal indication. The purpose of the invention is to provide two or more additional intervals when actuated by a unit of traffic.

One example of the type of traffic signal controller suited for use with the invention is described in United States Patent 2,265,991 entitled "Traffic Control Apparatus." It is preferable that the controller be of the traffic actuated type so that timing of one of the intervals may be stopped. If the invention is to be added to Phase A, for example, the controller timing circuit will be interrupted during one of the phase A intervals to permit the auxiliary intervals to be inserted. The auxiliary traffic signal lights are energized and controlled from the auxiliary timing unit. The existing controller and traffic signal wiring need not be disturbed; the auxiliary unit is merely connected into the controller terminal panel wiring.

Another use of the auxiliary timer unit is in conjunction with a minor movement controller. Normally, at an intersection of two streets with a third smaller street, a two phase controller with a minor movement is employed. The traffic signals may dwell giving the right of way to the main street. When a vehicle approaching on the cross street actuates the detector, the right of way is given to the cross street. If the right of way is with the cross street when a vehicle approaches from the minor street, the controller gives the right of way to main street before giving it to the minor street. This is necessary because the minor movement is associated with the cross street movement and can start only from the beginning

2

of the cross street phase. The only way to get into the cross street phase is through the main street phase.

The invention provides in-phase cycling of such a minor movement controller. That is, if right of way is presented to the cross street when the minor street detector is actuated by an approaching vehicle, right of way is given to the minor street without going street movement, thus making for more efficient traffic flow. Of course, a three phase controller could have been employed at the intersection. A three phase controller has the ability to skip streets having no traffic and would relieve the condition described. However, minor intersections do not warrant the expenditure for a three phase controller. The invention makes it economically feasible to improve traffic flow at such intersections at modest cost.

The principle object of the invention is to provide an auxiliary electronic timing unit for use with an intersection traffic controller.

Another object is to provide a unit which adds one phase to an existing intersection traffic controller.

Another object is to provide a timing and control unit which upon actuation adds one or more pedestrian or traffic moving intervals.

Another object is to provide an auxiliary multi-interval electronic timer started into operation by actuation of a pedestrian pushbutton to control and time pedestrian signals and prevent the intersection traffic signal controller from showing conflicting signals.

Another object is to provide an auxiliary multi-interval electronic timer started into operation by traffic actuation on a minor street which inserts one or more traffic moving intervals within one of the normal traffic moving phases.

Another object is to provide an auxiliary timing unit which converts a two phase controller to three phase operation.

Another object is to provide an auxiliary pedestrian actuated electronic timing unit to control and time the illumination of walk-wait traffic signals.

Another object is to provide an electronic circuit initiated through a timed signal display sequence controlled by and also controlling an intersection traffic controller.

Another object is to provide a timer which will control and time pedestrian traffic signals through walk and guaranteed clearing intervals upon pedestrian actuation prior to the walk interval, and upon pedestrian actuation during the guaranteed clearing interval if no vehicle actuation has occurred on the opposite phase.

Another object is to provide an electronically timed pedestrian interval timer having a memory device which will remember pedestrian actuations made during times when the walk sequence cannot be awarded almost immediately.

Another object is to provide a delayed green interval timer unit for use with an intersection traffic signal controller which will illuminate and time a signal display which will permit vehicles to clear a boulevard crossing after the normal right of way interval has transpired.

Another object is to provide a selective circuit which will reduce the guaranteed wait interval and permit the walk signal to be illuminated almost immediately after a pedestrian actuation during the guaranteed wait interval only if no vehicle actuations have occurred on the other phase.

Other objects and advantages will be disclosed throughout the description which follows. Reference will be made to the following drawings in which

FIGURE 1 is an isometric view of the exterior of the interval timer in its housing.

FIGURE 2 is a side view of the timer chassis with housing removed showing the electric components.

FIGURES 3, 4, and 5 are plan views of an intersection controlled by a two phase full-actuated controller with the auxiliary unit interconnected.

FIGURE 6 is a line to line schematic diagram of the timer circuit.

FIGURE 7 is a line to line diagram of the timing capacitor charging circuit.

FIGURE 8 is a line to line diagram of one of the timing circuits.

A general view of the timer unit is shown in FIGURE 1. The housing is comprised of a rectangular canister 1 having one open end 2 closed by a rectangular cover 3 to which the chassis is assembled. Two multi-pin connector plugs 4, 5 are inset into the face of the timer. Connector 4 has eleven pins through which connection is made to the terminal facilities within the intersection traffic signal controller cabinet, not shown. Connector 5 has nine pins through which connection is made to auxiliary apparatus also within the controller cabinet, not shown. Connectors 4 and 5 are standard; a wiring harness having cooperating eleven terminal and nine terminal sockets are normally provided to facilitate permanent connection into the terminal facilities. The timer unit may be removed or replaced simply by disconnecting the two connectors.

Two manual adjustment knobs 6, 7 are provided on the face of the unit to permit adjustment of the duration of the timed intervals. Gradations of dials 8, 9 indicate the duration of each interval. The unit shown in FIGURE 1 carries the designation "Walk" below dial 8 and "Clearance" below dial 9. The inscriptions may be changed to reflect the usage of the timer as, for example, "Delayed Green" and "Traffic Clearing" in another application of the invention described. Normally, the settings are made when the unit is first applied at an intersection and remain unchanged thereafter until intersection or other conditions change.

A side view of the timer unit is shown in FIGURE 2 with the canister removed. The formed chassis 10 is attached to the cover 3, and supports most of the electric components. The step switch CR1 is located on the upper level of the chassis. The check circuit relay CR2 is shown immediately below. The detector relay CR3 is hidden behind the transfer relay CR5. Both are attached to the vertical portion of the chassis 10. The load relay CR4 is hidden behind the transfer relay CR6. Both are located on the lower rear of the chassis. Plate circuit relay CR7 is attached to a bracket above relay CR6. The various resistors and capacitors shown in the schematic diagram of FIGURE 6 are mounted on insulated panel 18. The filament heater transformer is shown at 19, and the gas-filled tetrode tube V1 above it. Potentiometer R1 which controls the duration of the walk interval is shown mounted through front cover 3; potentiometer R2 which controls the duration of the clearance interval is located directly behind potentiometer R1. The wiring has been omitted from FIGURE 2 in the interest of clarity.

The step switch CR1 is of the OCS type shown more fully on page 88 of Automatic Electric Company bulletin entitled "Relays and Switches for Industrial Control," 1958. As illustrated in FIGURE 2 herein three cams 11, 12, 13 control the operation of contacts CR1-1B and CR1-1C, CR1-2B and CR1-2C, and CR1-3B and CR1-3C, respectively. The B in the contact nomenclature indicates a B stack, or a pair of normally closed contacts; C indicates a C stack, or single pole, double throw contacts. The cams 11, 12, 13 are cut according to the inset shown as part of FIGURE 6. Cams 11 and 13 are cut in the first or reset interval. Cam 12 is cut in the second or walk interval. The B stack is closed during the cut interval. The C stack transfer during the cut interval. FIGURE 6 is drawn to illustrate the position of the contacts during the first or reset interval.

Step switch CR1 also carries two sets of interrupter contacts which are actuated when coil CR1-C is energized. Contacts CR1-INT-B are interrupter contacts, B stack, normally closed, and open while coil CR1-C is energized. Contacts CR1-INT-C are interrupter contacts, C stack, which transfer while coil CR1-C is energized.

INSTALLATION

10 The auxiliary electronic timer unit may be used in conjunction with an intersection traffic controller to accomplish a variety of control functions. The most important applications are as a pedestrian walk and guaranteed clearance interval timer, as a minor phase movement and clearance interval timer, or as a delayed green and clearance interval timer. In each of these applications the auxiliary unit is actuated into its timing and traffic signal controlling sequence by traffic actuation. Actuation is by pedestrian pushbutton in the first named application or by vehicle detector in the vehicle con-

20 trolling applications.

The intersection traffic signal controller to which the unit is connected is normally a two phase unit, either semi-actuated or full-actuated. Semi-actuated controllers 25 have traffic detectors in one intersecting street, usually the minor or cross street. Full-actuated controllers have detectors in both intersecting streets. The auxiliary unit may be connected into the cross street phase and used as a pedestrian unit to permit pedestrians to cross the 30 main street while the cross street traffic is moving. Or it may be connected into the main street phase to permit pedestrians to cross the minor street while main street traffic is moving. If used as a minor movement timer unit it permits minor movements such as left turns during 35 a portion of the main street phase. If used as a delayed green timer unit it is connected to be actuated once each cycle to provide additional signal indications—such as a delayed green movement across a wide boulevard.

40 The auxiliary unit is operated in conjunction with the compatible phase of the traffic signal cycle. The function of the auxiliary unit is to call the controller to the compatible phase, permit non-interfering traffic to flow, retain the controller in that phase until the inserted intervals have transpired, and then return control to the intersection controller.

45 The various traffic movements are illustrated in FIGURES 3, 4, and 5. The phase A movement which corresponds to traffic flow on street 14 is shown in progress in 50 FIGURE 3. Since traffic is permitted to flow across cross walk 18 the DON'T WALK signals 19 are illuminated. Traffic is stopped on street 15.

A pedestrian wishing to cross street 14 depresses one of the pushbuttons PB located at each corner of the intersection and waits for the WALK signal. The WALK signal is illuminated after the proper clearance signal is given to phase A traffic on street 14. Traffic is stopped on street 14 and permitted to flow on street 15. The WALK signals 19 are illuminated for a time and then extinguished. The DON'T WALK signals are then illuminated for a guaranteed pedestrian clearance interval. At the expiration of the guaranteed clearance interval right of way is returned to street 14 if a detector actuation has occurred thereon.

60 A second condition is illustrated in FIGURE 4. The phase B traffic movement is in progress with traffic flowing on street 15 and stopped on street 14. If a pedestrian arrives at the intersection while the phase B movement is in progress and wishes to cross street 14 he depresses one of the pushbuttons PB and is given the WALK light almost immediately if no vehicle has actuated one of the phase A detectors DA. The function of the auxiliary unit under this condition is to illuminate and time the WALK signals 19, and then to extinguish the WALK signals and illuminate the time the DON'T WALK signals

for a guaranteed pedestrian clearance interval. At the expiration of the guaranteed clearance interval the auxiliary unit 17 transfers control back to the intersection controller 16.

A third condition is illustrated in FIGURE 5. The phase B movement is in progress with traffic moving on street 15 and stopped in street 14. A vehicle V has crossed detector DA and has entered a call to the intersection controller 16. A pedestrian desiring to cross street 14 at this time and depressing one of the push-buttons PB will not be given the WALK signal immediately even though the controller 16 is in the compatible phase. The circuit is designed to award right of way on a first come, first served basis and will grant right of way to vehicle V before granting right of way to the pedestrian.

While vehicle V is being granted the right of way additional vehicles may arrive at the intersection and actuated detectors DA. They will extend the time right of way is given to street 14 but they will not be able to retain right of way longer than a phase A maximum period. Then right of way will be returned to the phase B movement at which time the WALK signals will be illuminated. The WALK signals will be extinguished after a short interval and the DON'T WALK signals illuminated for a guaranteed pedestrian clearance interval. After the guaranteed interval the auxiliary unit will relinquish control and the right of way will be returned to street 14 if the phase A maximum period has expired or if another actuation occurs on street 14.

These three conditions are enumerated below. The operation of the auxiliary unit will be described with reference to each of these conditions.

Condition 1. The intersection controller is dwelling in phase A with the right of way signals illuminated to street 14 permitting traffic to cross the pedestrian's path. No vehicle calls are in when the pedestrian pushbutton PB is depressed. This condition is illustrated in FIGURE 3.

Condition 2. The intersection controller is dwelling in phase B with the right of way signals illuminated to traffic on street 15 parallel with the pedestrian crosswalk. No vehicle calls are in when the pedestrian pushbutton PB is depressed. This condition is illustrated in FIGURE 4.

Condition 3. The intersection controller is in phase B illuminating the right of way signals on street 15 to traffic parallel with the pedestrian crosswalk. A vehicle V has actuated the vehicle detector DA and has approached the pedestrian crosswalk when the pushbutton PB is depressed. This condition is shown in FIGURE 5.

The functioning of the auxiliary unit through its various phases will be described with reference to FIGURE 6. FIGURE 6 is in the form of a line to line schematic wiring diagram of the device. The relay coils CR1-C to CR7-C are arranged across the sheet in spaced apart relationship. Contacts associated with each relay are shown in vertical alignment with their controlling coils, for the most part, so that reference is facilitated. The input and control terminals 28-39 are located along the left margin of the drawing. The common return line 40 is drawn along and parallel to the right margin.

The operation of the timing and control circuit will be described following operation of the detector actuator during each of three conditions enumerated above.

Condition 1

As defined above, condition 1 exists when the intersection traffic signal controller is dwelling in the opposing phase, phase A, with no recent vehicle actuation when a call is placed on the auxiliary unit. A call is placed when a pedestrian depresses the pushbutton PB. The pushbutton PB admits L1 power to terminal 30. Power flows from a 12 volt source, through the 12 volt terminal 31, through lead 41, the coil CR3-C of relay CR3, lead 43, terminal 38, and to ground through the pushbutton PB.

Relay CR3 is thus energized while the pushbutton (or other detector) is depressed. The various contacts on relay CR3 close or transfer. Contacts CR3-1 close to temporarily seal in relay CR3 through lead 44, contacts CR1-2C, lead 45, and common line 40. Contacts CR1-2C are in the position shown because the timer is assumed to be dwelling in the reset interval. Contacts CR3-3 close permitting L1 power to flow to the phase B detector terminal on the intersection controller 16. This puts in a call to the controller to cause it to award right of way to phase B. It is necessary to stop traffic on street 14 before pedestrians can be allowed to cross. The circuit includes L1 line 40, lead 45, contacts CR1-2C, lead 44, lead 46, closed contacts CR5-2, lead 47, now-closed contacts CR3-3, lead 48, lead 49, phase detector terminal 29, to the detector terminal for the phase B.

Contacts CR3-4 close and permit L1 power to flow to the phase B density detector terminal 36. The circuit includes L1 line 40, lead 68, contacts CR1-3C, lead 94, now-closed contacts CR3-4, lead 95, contacts CR5-4, lead 96, and terminal 36. L1 power applied to the phase B density detector terminal of a volume-density type intersection controller aids in urging the intersection controller to the phase B movement which is compatible with the pedestrian movement.

Contacts CR3-5 close to complete an auxiliary control circuit through terminal 22, lead 62, now-closed contacts CR3-5, lead 63 and terminal 23. The auxiliary control circuit may be employed to condition auxiliary equipment to restrain it from operation until the pedestrian cycle is completed for example.

Contacts CR3-2 also close when the pedestrian pushbutton PB is depressed. They admit L1 power to energize the step switch relay coil CR1-C. The circuit is from L1 line 40, lead 51, contacts CR1-1B, lead 52, interrupter contacts CR1-INT-B, lead 53, now-closed contacts CR3-2, lead 54, through the parallel circuits consisting of lead 56, contacts CR2-1, lead 57, and lead 55, contacts CR5-3, lead 58, through lead 59, step switch relay coil CR1-C, lead 93, rectifier DR3, lead 60, to L2 power terminal 20.

When step switch relay coil CR1-C is energized it opens interrupter contacts CR1-INT-B and transfers interrupter contacts CR1-INT-C. Opening the former contacts de-energizes step switch relay coil CR1-C. The transfer of the later contacts has no effect on the circuit because another contact CR1-1C in series with them is open.

When step switch relay coil CR1-C is deenergized it ratchets the step switch CR1 into the walk interval. Reference may be made to the step switch contact diagram inset in FIGURE 6. Contacts CR1-1B open, contacts CR1-2B close, and contacts CR1-3B open. Contacts CR1-1C, CR1-2C, and CR1-3C transfer.

The unit is now in the walk interval but the WALK signals are not yet illuminated and timing has not yet started.

Contacts CR1-1B open and disconnect the portion of the circuit which energized the step switch CR1 out of the reset interval. Another portion of the circuit which includes the plate circuit relay CR7 and the two timing circuits now comes into play.

Contacts CR1-2B close to ready the circuit including the load relay coil CR4-C.

Because the intersection controller has been given a call, it deenergizes the right of way signal on street 14 (phase A) and illuminates the amber signal. At the end of the clearing interval the amber signal is deenergized and the stop signal illuminated. The right of way is given to street 15 with the energization of the phase B green signal. Energy is also supplied to the phase B green signal terminal 34.

When terminal 34 is energized from the right of way signal circuit controlled by the intersection controller power flows over lead 64 to energize relay coils CR4-C, CR5-C, and CR6-C. One circuit includes lead 64, now-

closed contacts CR1-2B, lead 65, relay coil CR4-C, lead 66, to L1 return 40. The second circuit includes lead 64, relay coil CR5-C, lead 66, and L1 return 40. The third circuit includes lead 64, relay coil CR6-C, lead 67, now-transferred contacts CR1-3C, lead 68, and L1 return 40. L1 power is fed out on terminal 35 over lead 68, now-transferred contacts CR1-3C, lead 67, lead 69, and terminal 35 for other control purposes.

Relay coils CR4-C, CR5-C, and CR6-C actuate their respective contacts simultaneously. Their action will be described individually after the timing and charging circuits are explained.

The timing of the walk and guaranteed clearance intervals is effected through an RC timing circuit including capacitor C1 and resistors R3 and R9. The charging circuit is shown by itself in FIGURE 7. The cathode 72 and the screen grid 73 within tube V1 are employed as a rectifier to permit line voltage to charge capacitor C1. When line L2 is negative with respect to line L1 the charging circuit includes L2 terminal 24, lead 71, cathode 72, grid 73, current limiting resistor R4, timing capacitor C1, lead 74, contacts CR5-1, lead 75, and L1 return 40. During the half cycle when line L2 is positive with respect to line L1 no current flows in the reverse direction because of the rectifier action of tube V1. The left side of capacitor C1 charges to peak line potential of -150 volts. This negative potential prevents tube V1 from conducting.

The discharge or timing circuit for capacitor C1 includes resistor R9, variable resistor R3, and lead 81. Variable resistor R3 is set to provide a sufficiently long delay interval. The duration of the walk and clearance intervals are determined also by the voltage divider circuits which include potentiometers R1, R2, resistor R5, R6, linearity resistors R7, R8, and coupling resistor R10.

The timing circuit for the walk interval is shown by itself in simplified form in FIGURE 8. Line voltage is applied across the potential divider consisting of potentiometer R1 and resistor R5. The circuit includes L2 terminal 24, lead 71, lead 76, lead 77, resistor R5, potentiometer R1, lead 78, and L1 return 40. During the half cycle when line L2 is positive with respect to line L1, tube V1 is prevented from firing because a positive potential is applied to its cathode 72 and a negative potential is applied to its plate 80. During the half cycle when line L1 is positive with respect to line L2, the timing capacitor C1 is carried positive by an amount determined by the setting of the potential divider R1, R5. Assume for example that the potential divider R1, R5 is set to provide +50 volts on lead 79. This +50 volts is applied to the right side of capacitor C1 from L1 line 40, through lead 78, part of potentiometer R1, lead 79, contacts CR4-2 when transferred, coupling resistor R10, and lead 81. This makes the potential appearing on the left side of capacitor C1 less negative, and with the decay of potential on capacitor C1 due to current leakage through timing resistors R9 and R3, the grid 73 becomes sufficiently less negative to permit tube V1 to fire.

Having described the operation of the timing circuits the function of relays CR4, CR5, and CR6 will now be explained.

When the phase B green signal was energized indicating that the walk interval could start, terminal 34 was energized. Relay coils CR4-C, CR5-C, and CR6-C were energized as described above. Contacts CR4-1 transfer energizing the WALK signals and deenergizing the DON'T WALK signals. The signal lights are placed across street 14 and permit pedestrians to cross street 14 when the WALK signal is illuminated. Power is fed from L2 terminal 24, through lead 71, lead 76, lead 84, now transferred contacts CR4-1, lead 86, to WALK signal terminal 26. Power is removed from lead 85 and DON'T WALK signal terminal 25.

Contacts CR4-2 transfer and complete the walk interval timing circuit shown in FIGURE 8. Timing of the walk interval may be set for 10 seconds, for example, to

allow a number of pedestrians to start across the street. Across busy thoroughfares the walk interval may be reduced to prevent undue delay to main street vehicular traffic. The walk interval has no relationship to the time it takes to cross the street. This is the clearance interval and is timed during the next period.

Contacts CR5-1 transfer and complete the plate circuit which includes plate 80, relay coil CR7-C, lead 82, interrupter contacts CR1-INT-C, lead 83, now-transferred contacts CR1-1C, lead 87, now-transferred contacts CR5-1, lead 75, and L1 return 40. Tube V1 does not fire as soon as contacts CR5-1 transfer; it must wait until the negative potential applied to grid 73 has decayed sufficiently to permit firing.

When contacts CR5-1 transfer they open the normal charging circuit for capacitor C1. When capacitor C1 is to be charged again between the walk and the clearance intervals it is charged over a different circuit which is described below.

Contacts CR5-2 open to prevent a backfeed from sealing in the pedestrian actuated relay CR3 if the pushbutton PB is pressed during the walk or clearance intervals. Without contacts CR5-2 the circuit would be completed from L1 return line 40, lead 78, lead 88, lead 89, now-transferred contacts CR6-1, lead 48, momentarily closed contacts CR3-3, lead 47, lead 46, momentarily closed contacts CR3-1, relay coil CR3-C, lead 42, lead 41, and the twelve volt supply terminal 21.

Contacts CR5-3 open to break one-half of the parallel circuit to step switch relay coil CR1-C. Contacts CR5-3 and CR2-1 are both open under Condition 3 and will be described in that section.

Contacts CR5-4 open to break the call placed on the phase B density detector terminal 36. The call was actually broken when contacts CR1-3C transferred at the beginning of the walk interval. The function of the phase B density detector terminal 36 was explained above.

Contacts CR6-1 transfer and remove L1 power from the density yield terminal 28 and lead 90. L1 power is applied to the phase B detector terminal 29 over lead 49. Contacts CR6-1 are transferred and feed L1 power to detector terminal 29 all during the walk and clearance intervals to place a continuous call on the intersection traffic signal controller to maintain it in phase B. After the guaranteed clearance interval has transpired contacts CR1-3C transfer and open the L1 circuit to relay coil CR6-C. Contacts CR6-1 transfer back to the position shown in FIGURE 6 and remove the call from the phase B detector terminal 29. The intersection traffic controller is then free to answer calls on the other street.

Contacts CR6-2 transfer, breaking the auxiliary control circuit between terminals 37 and 38 and making the auxiliary control circuit between terminals 38 and 39. A left or right turn arrow might be turned off by the opening of the first contacts and a flasher might be energized through the closing of the second contacts to flash the DON'T WALK signals during the guaranteed clearance interval.

The walk interval expires when the voltage on grid 73 decays below the value required to prevent conduction. Tube V1 fires, energizing relay coil CR7-C. During the half cycle when the plate 80 is positive electrons flow from L2 terminal 24, over lead 71, cathode 72, plate 80, relay coil CR7-C, lead 82, contacts CR1-INC-C, lead 83, now-transferred contacts CR1-1C, lead 87, now-transferred contacts CR5-1, lead 75, to L1 return 40.

Relay contacts CR7-2 close and energize step switch relay coil CR1-C. During one half cycle current flows from L1 line 40, lead 91, now-closed contacts CR7-2, lead 92, step switch relay coil CR1-C, lead 93, diode rectifier DR3, lead 60, to L2 terminal 29. During the next half cycle no current flows between lines L2 and L1 because of the high back impedance of diode rectifier DR3. The decay current of coil CR1-C is maintained through diode

rectifier DR2, however, to increase the average current through the coil.

As the step switch coil CR1-C is energized it pulls in its armature and near the end of travel transfers the interrupter contacts CR1-INT-C. This breaks the plate circuit and also provides a path for charging the timing capacitor C1. The circuit includes L2 terminal 24, lead 71, cathode 72, grid 73, limiting resistor R4, capacitor C1 lead 74, now-transferred contacts CR1-INT-C, lead 83, contacts CR1-1C, lead 87, now-transferred contacts CR5-1, lead 75, and L1 return 49. Current flows only during the half cycle when the grid 73 is positive with respect to the cathode 72.

The step switch relay coil CR1-C is energized for only a short period because the transfer of interrupter contacts CR1-INT-C opens the plate circuit and deenergizes relay coil CR7-C. Contacts CR7-2 open and deenergize step switch relay coil CR1-C. On the deenergized stroke the armature steps the step switch out of the walk interval and into the clearance interval. Interrupter contacts CR1-INT-C transfer back to the position shown in FIGURE 6 and complete the plate circuit.

Contacts CR1-2B open and deenergize relay coil CR4-C. Contacts CR4-2 transfer back to the position shown in FIGURE 6 and insert the potential divider consisting of resistors R2 and R6 into the timing circuit. Contacts CR4-1 transfer back to the position shown in FIGURE 6 deenergizing the WALK signal terminal 26 and energizing the DON'T WALK signal terminal 25. The clearance interval is set to provide sufficient crossing time for a pedestrian stepping off the curb when the WALK light is extinguished. Consideration must be given to slower walking persons to permit them sufficient time to cross the intersection.

The guaranteed clearance interval expires when the voltage remaining across capacitor C1 is no longer sufficient to prevent conduction of tube V1. When tube V1 fires, relay coil CR7-C is energized. Contacts CR7-2 close and energize step switch relay coil CR1-C. As the coil is energized its armature actuates interrupter contacts CR1-INT-C interrupting the plate circuit and deenergizing plate circuit relay coil CR7-C. Contacts CR7-2 open and deenergize the step switch relay coil CR1-C. On the deenergized stroke the armature steps the step switch out of the clearance interval and into the reset interval where it resides until the next pedestrian actuation.

Contacts CR1-1B close as shown in FIGURE 6 preparing the circuit containing leads 52-59 for the next actuation.

Contacts CR1-1C transfer to the position shown in FIGURE 6. When contacts CR5-1 move to the position shown they complete the timing capacitor C1 charging circuit.

Contacts CR1-3C transfer to the position shown so that when contacts CR5-4 close with the passage of the phase B green signal a call will be entered on the phase density detector terminal 36 when contacts CR3-4 close momentarily with a new pedestrian actuation. The circuit includes L1 return 49, lead 68, contacts CR1-3C, lead 94, contacts CR3-4, lead 95, contact CR5-4, lead 96 to phase B density detector terminal 36. The auxiliary unit is thus ready for a new actuation.

Condition 2

Condition 2 has been defined as the condition when the intersection controller is dwelling in phase B with the right of way signals illuminated to traffic on street 15 parallel with the pedestrian crosswalk 18. No vehicle actuations have occurred when the pedestrian pushbutton PB is depressed. The condition of the auxiliary unit just prior to pushbutton actuation will be described.

Referring to FIGURES 4 and 6, the phase B green traffic signals are illuminated and the phase B green terminal 34 is energized. Therefore relay coil CR5-C is energized. Contacts CR5-1 have transferred and provide a path for

maintaining the charge on timing capacitor C1. Contacts CR5-2 are open and will prevent relay coil CR3-C from sealing in when the pushbutton is depressed. Contacts CR5-3 are open. Contacts CH2-1 are closed because no vehicle actuation has occurred on the other phase. If a call had been entered on street 14 the check circuit terminal 32 would have been energized with L1 power and relay coil CR2-C energized over lead 61. Contacts CR5-4 are open preventing energization of the phase B density detector terminal 36.

Relay coils CR4-C and CR6-C are not energized because their leads are open through contacts CR1-2B and CR1-3C, respectively, as shown in FIGURE 6.

When one of the pushbuttons PB in FIGURE 4 is depressed, terminal 30 in FIGURE 6 is placed at L1 potential. The circuit to relay coil CR3-C is completed and relay CR3 is energized. Contacts CR3-1 close momentarily sealing in relay coil CR3-C through contacts CR1-2C. Contacts CR3-2 close and energize step switch relay coil CR1-C through contacts CR1-1B, CR1-INT-B, CR3-2 and CR2-1. Energization of the step switch relay coil CR1-C causes its armature to actuate the interrupter contacts CR1-INT-B and CR1-INT-C. The former interrupt the circuit to coil CR1-C deenergizing the step switch. The latter transfer momentarily but have no effect at this time. Deenergization of step switch coil CR1-C causes its armature to step the switch into the walk interval.

At the beginning of the walk interval all of the step switch contacts reverse positions.

Contacts CR1-1B open making the circuit containing leads 51-59 inoperative during the walk and clearance intervals. Contacts CR1-1C transfer and complete the plate circuit of tube V1.

Contacts CR1-2B close and energize load relay coil CR4-C. Contacts CR1-2C transfer and break the sealing circuit for the detector relay coil CR3-C.

Contacts CR1-3C transfer and remove the L1 call from the phase B density detector terminal 36. In transferring they complete the L1 circuit to relay coil CR6-C permitting it to be energized.

When relay coil CR4-C is energized, contacts CR4-1 transfer and extinguish the DON'T WALK signals and illuminate the WALK signals. Contacts CR4-2 transfer and complete the walk timing circuit shown also in FIGURE 8. The walk interval is now timing.

When relay coil CR6-C is energized, contacts CR6-1 transfer and remove L1 power from the density yield terminal 28 and place a continuous call on the phase B detector terminal 29. Contacts CR6-2 transfer for auxiliary control control purposes.

The walk interval is still timing. When the net potential on the left side of timing capacitor C1 is no longer sufficient to prevent conduction, tube V1 fires, energizing plate circuit relay coil CR7-C. Contacts CR7-2 close and energize step switch relay coil CR1-C. Upon energization, interrupter contacts CR1-INT-B and CR1-INT-C are actuated. The former open but have no effect. The latter transfer and perform two functions. They open the plate circuit of tube V1 and deenergize coil CR7-C, and they close the charging circuit for timing capacitor C1.

When coil CR7-C is deenergized, contacts CR7-2 open and deenergize the step switch relay coil CR1-C. The step switch steps out of the walk interval and into the clearance interval. Contacts CR1-INT-C retransfer to the position shown in FIGURE 6, breaking the charging circuit and completing the plate circuit.

Contacts CR1-2B open and deenergize the transfer relay CR4. Contacts CR1-2C remove L1 power from auxiliary control terminal 33 and close the memory circuit to the detector relay coil CR3-C. Contacts CR4-1 transfer and deenergize the WALK signal terminal 26 and energize the DON'T WALK signal terminal 25.

The clearance interval is now timing. When the net potential on the left side of timing capacitor C1 can no

longer prevent conduction, tube V1 fires, energizing plate circuit relay coil CR7-C. Contacts CR7-2 close and energize the step switch relay coil CR1-C. Interrupter contacts CR1-INT-C transfer, breaking the plate circuit and completing the charging circuit to timing capacitor C1. Interruption of the plate circuit deenergizes relay coil CR7-C and opens contacts CR7-2, deenergizing the step switch relay coil CR1-C. The step switch ratchets out of the clearance interval and into the reset interval.

Contacts CR1-1B close to make the portion of the circuit containing leads 51-59 effective. Contacts CR1-1C transfers to close the charging circuit to timing capacitor C1. Contacts CR1-3C transfer and deenergize relay coil CR6-C. Contacts CR6-1 transfer and remove the continuous call from the phase B detector terminal 29 and place it on the density yield terminal 28.

The auxiliary timer unit is thus in the reset interval ready for another pedestrian actuation. It will answer pedestrian calls continuously in this condition until a vehicle actuation occurs on phase A. A vehicle actuation of detector DA as shown in FIGURE 5 causes a call to be entered on the intersection controller which feeds an L1 potential to the check circuit terminal 32 and energizes relay coil CR2-C. This fulfills the requirements for Condition 3.

Condition 3

It will be recalled that condition 3 is identical with Condition 2 except that a vehicle has approached on street 14 and actuated a detector DA as shown in FIGURE 5. The auxiliary timer unit is designed to award passage time to the various phases in the order of their actuation. Since a phase A vehicle actuation occurred prior to the pedestrian actuation, the controller will answer the vehicle call first. Actuation of detector DA will cause the intersection controller to apply L1 power to the check relay coil CR2-C. The phases B green signals energize terminal 34 which in turn will energize the transfer relay coil CR5-C and will attempt to energize relay coils CR4-C and CR6-C. Local relay coil CR4-C and transfer relay coil CR6-C will not be energized because their L1 leads are open through step switch contacts CR1-2B and CR1-3C, respectively, as shown in FIGURE 6. The pedestrian pushbutton PB has not yet been depressed and the step switch is in the reset interval.

When the pushbutton PB is depressed under these conditions the detector relay coil CR3-C is momentarily energized and is then sealed in through now-closed contacts CR3-1, lead 44, contacts CR1-2C, lead 45, and L1 return 49. Contacts CR3-2 close and attempt to energize the step switch relay coil CR1-C. It is prevented from doing so because contacts CR2-1 and CR5-3 are both open because relays CR2 and CR5 are both energized. Relay CR2 being energized indicates that a vehicle detector actuation has occurred on street 14. The auxiliary unit therefore remains in the reset interval until the intersection controller answers the phase A vehicle call. The intersection controller stops traffic on street 15 and awards right of way to street 14. When the phase B green signals are extinguished, terminal 34 and relay coil CR5-C are deenergized. Contacts CR5-3 close and energize step switch relay coil CR1-C. The interrupter contacts CR1-INT-B and CR1-INT-C are actuated. The former open and deenergize step switch relay coil CR1-C. The latter transfer but have no effect.

When coil CR1-C is deenergized the step switch moves into the walk interval but the WALK signals are not illuminated and timing does not start until the phase B green signals are again energized.

Contacts CR1-1B open and disconnect this path to the step switch relay coil CR1-C. Contacts CR1-1C transfer and close one of the gaps in the plate circuit. The other gap is not closed until contacts CR5-1 transfer when the phase B green signals are energized.

Contacts CR1-2B close and complete the circuit to

load relay coil CR4-C. Coil CR4-C is not energized until the phase B green signals are energized. Contacts CR1-2C transfer and break the memory circuit to the detector relay coil CR3-C. Relay CR3 is thus deenergized at the beginning of the walk interval. The WALK signals are not illuminated until the phase B green signals are energized.

Contacts CR1-3C transfer and break the L1 lead to the phase B density detector terminal 36, and make the L1 circuit to auxiliary control terminal 35.

The auxiliary unit is thus in condition to illuminate and time the WALK signal as soon as the right of way is returned to the street parallel with the pedestrian crosswalk. The total delay to the pedestrian is relatively short and is equal to the sum of the clearance interval to phase B traffic and the initial, vehicle, and clearance intervals to phase A traffic. The delay may total 10 to 15 seconds, for example, unless continued vehicles arriving on street 14 cause extension of the vehicle interval. The greatest delay which could occur is equal to the phase "A" maximum interval which is timed by the intersection controller.

As soon as the right of way signals are illuminated to the street parallel with the crosswalk the phase B green terminal 34 is energized and relay coils CR4-C, CR5-C, and CR6-C are energized because contacts CR1-2B are already closed and contacts CR1-3C are transferred as noted above.

Contacts CR4-1 transfer and extinguish the DON'T WALK signals and illuminate the WALK signals. Contacts CR4-2 transfer and complete the walk interval timing circuit. Contacts CR5-1 transfer and open the timing capacitor C1 charging circuit and complete the plate circuit. Contacts CR6-1 transfer and remove L1 power from the density yield terminal 28 and enter a continuous call on the phase B detector terminal 29 to hold the intersection controller in phase B for the duration of the walk and clearance intervals.

At the end of the walk interval the voltage appearing on the left side of timing capacitor C1 becomes insufficient to continue to prevent tube V1 from firing. Tube V1 fires and energizes plate circuit relay coil CR7-C which closes contacts CR7-2. Step switch relay coil CR1-C is energized and transfers interrupter contacts CR1-INT-C which break the plate circuit and close the charging circuit to timing capacitor C1. When the plate circuit is broken, contacts CR7-2 open and deenergize the step switch relay coil CR1-C. The step switch ratchets its cams into the guaranteed clearance interval and contacts CR1-2B open and contacts CR1-2C transfer. The opening of contacts CR1-2B deenergizes load relay coil CR4-C.

Contacts CR4-1 transfer back to the position shown in FIGURE 6, extinguishing the WALK signal and illuminating the DON'T WALK signal. Contacts CR4-2 transfer to the position shown in FIGURE 6 and connect the clearance interval timing circuit. The guaranteed clearance interval is thus timing.

When contacts CR1-2C transfer to the position shown in FIGURE 6 they restore the detector relay memory circuit which may be completed to seal in detector relay coil CR3-C when the pedestrian pushbutton PB is again depressed. If no vehicle detector actuations occur on phase A the pedestrian unit can continue to answer pedestrian calls.

Near the end of the guaranteed clearance interval the charge and potential remaining on capacitor C1 becomes insufficient to keep tube V1 from firing. Tube V1 fires and energizes plate circuit relay coil CR7-C. Contacts CR7-2 close and energize the step switch relay coil CR1-C. Interrupter contacts CR1-INT-C transfer and open the plate circuit and close the charging circuit. Opening the plate circuit deenergizes the step switch relay coil CR1-C and causes it to rotate its cams out of the clearance interval and into the reset interval.

Contacts CR1-1B close as shown in FIGURE 6 to make the portion of the circuit containing leads 51-59 effective when the detector relay CR3 is energized. Contacts CR1-1C transfer and open the plate circuit and close the charging circuit. Contacts CR1-3C transfer as shown in FIGURE 6. The auxiliary unit is thus in its reset condition.

PEDESTRIAN RECALL

A circuit is provided within the auxiliary unit to permit a pedestrian actuating the pushbutton during the clearance interval to obtain a walk indication immediately if no vehicle actuation has occurred on the opposite phase, phase A. The circuit includes relay contacts CR2-2 and CR3-6, FIGURE 6.

When the unit is timing the guaranteed clearance interval and the pedestrian pushbutton is depressed, detector relay coil CR3-C is energized. Contacts CR3-1 close and seal in relay coil CR3-C through contacts CR1-2C and leads 44, 45. Contacts CR3-6 transfer and admit L1 potential to the right side of timing capacitor C1 from L1 return 49, through lead 97, contacts CR2-2, lead 98, now-transferred contacts CR3-6, contacts CR4-2, coupling resistor R10 and lead 81. During the half cycle in which L1 line 40 is positive with respect to line L2, the net voltage appearing on the left side of timing capacitor C1 is positive and permits tube V1 to fire. The step switch ratchets out of the clearance interval and into the reset interval in the manner described previously.

In the reset interval contacts CR1-1B close as shown in FIGURE 6 and since detector relay contacts CR3-2 are already closed, the step switch coil CR1-3 is energized. The circuit includes L1 line 40, lead 51, contacts CR1-1B, lead 52, contacts CR1-INT-B, lead 53, contacts CR3-2, lead 54, lead 56, contacts CR2-1, lead 57, lead 59, step switch coil CR1-C, lead 93, diode rectifier DR3, lead 60, to L2 terminal 20.

Upon energization of the step switch coil CR1-C interrupter contacts CR1-INT-B open and deenergize step switch coil CR1-C. The step switch moves out of the reset interval and into the walk interval. At the beginning of the walk interval, contacts CR1-2B close and energize the load relay coil CR4-C. Contacts CR4-1 transfer and illuminate the WALK signal and contacts CR4-2 complete the walk timing circuit as described previously. The timer has thus answered another pedestrian call substantially immediately after actuation during the clearance interval.

The above cycle would have been delayed if a vehicle actuation had occurred on phase A as in FIGURE 5 because check relay CR2 would have been energized from the intersection controller. Contacts CR2-2 would have transferred out of the position shown in FIGURE 6 thus connecting the normal clearance timing circuit back into the circuit. The walk interval would be delayed until the intersection controller answered the call on phase A and then returned to phase B. Contacts CR2-1 would also be open preventing the step switch coil CR1-C from being energized when contacts CR3-2 are closed by pushbutton actuation. The memory circuit seals in and remembers the pedestrian call until the unit can answer it. This is the same as Condition 3.

The function of the various terminals 20-39 not already explained in detail will now be explained.

MANUAL FEATURE

During periods of abnormally heavy traffic flow as may occur for example after a sporting event it may be desired that a traffic officer have control of the traffic signals. A key switch, not shown, may be provided on the intersection controller cabinet to make the normal timing circuits in the controller ineffective and to connect a hand operated pushbutton into the control circuits. The pushbutton energizes the ratchet motor within the

intersection controller. Upon release of the pushbutton the ratchet motor is deenergized and ratchets the cam-shaft into the next interval thus changing the traffic signal indication.

5 During manual operation of the intersection controller it is desired that the pedestrian sequence be inserted once each cycle during the compatible vehicle right of way interval. That is, the walk and clearance intervals are to be inserted during the phase B green portion of the 10 cycle for a time determined by the officer and not to exceed the times preset on the timing dials.

A transfer relay within the intersection controller is energized during the phase B right of way interval to transfer the pushbutton initiated impulses from the ratchet 15 motor in the intersection controller to manual terminal 21 of the auxiliary unit. The impulses energize the step switch coil CR1-C and cause it to step the step switch during the proper interval of the phase B right of way period. The circuit includes manual terminal 21, lead 99, lead 59, coil CR1-C, lead 93, diode rectifier DR3, lead 60, and L2 terminal 20. The contacts controlled by the step switch do not change until the step switch coil CR1-C is deenergized. In the walk interval contacts CR1-2B are closed and since phase B green signals are energized, lead 25 relay coil CR4-C is energized. Contacts CR4-1 transfer and illuminate the WALK signals and extinguish the DON'T WALK signals.

Timing of all intervals is done by the officer unless they exceed the times preset on the timing dials. He 30 may terminate the walk interval and start the clearance interval by pressing and releasing the manual pushbutton, ratching the step switch CR1. The WALK signals are extinguished and the DON'T WALK signals illuminated by the retransfer of load relay contacts CR4-1.

35 When the officer desires to terminate the pedestrian clearance interval he presses and releases the manual pushbutton. A second relay in the intersection controller has opened the impulse transfer circuit during the clearance interval to permit the manual control to again be connected to the ratchet motor in the intersection controller and disconnected from the step switch in the auxiliary unit. This transfer relay may be energized from auxiliary control terminal 35 which is energized during the walk and clearance intervals through contacts CR1-3C.

40 Thus a phase of pedestrian movement is included in each manually controlled cycle.

AUXILIARY CONTROL CIRCUIT

The auxiliary control circuit including terminals 22 and 50 23 and detector relay contacts CR3-5 is provided to eliminate an external relay normally required when the auxiliary timer unit is used with a railroad or other preemptor circuit. A pilot light may also be connected in circuit with a source of power and terminals 22, 23 to indicate when a pedestrian actuation has occurred and a call is in.

55 When used in conjunction with a railroad preemptor, the terminals 22, 23 are connected to the preemptor to indicate when a pedestrian call is in. The preemptor 60 circuit may then include a pedestrian phase with a railroad actuated phase, or if the intersection configuration prevents this, delay the pedestrian phase until a compatible vehicle phase.

65 This circuit eliminates an external relay.

POWER TERMINAL L2

Power for the auxiliary unit is supplied to L2 terminal 24. Potential is fed over lead 71 to the cathode 72 of tube V1, to the screen grid 70 of tube V1. Power flows over lead 76 to the primary coil of filament heater transformer T1, over lead 84 to the WALK and DON'T WALK signals, and over lead 77 to the walk and clearance timing circuits. The other end of the primary coil of transformer 75 T1 is connected to L1 line 88. The center tap of the low

voltage side of transformer T1 is connected to L2 line 76 over lead 50. L2 power is also supplied at terminal 20.

DENSITY YIELD

The density yield terminal 28 is connected to L1 line 40 through normally-closed contacts CR6-1 to permit an intersection controller of the density type to operate. A density type controller is here defined as one which weighs the arrival of vehicular traffic during the red signals and adjusts the initial portion of the green signal duration on the opposite phase accordingly. When L1 power is removed from terminal 28, as during the walk and guaranteed clearance intervals, the intersection controller is prevented from stepping to the next interval. After the clearance interval, contacts CR6-1 close again and permit the intersection controller to operate.

PHASE DETECTOR TERMINAL

The traffic detector relay for the vehicle phase compatible with the pedestrian phase is connected to the phase detector terminal 29. It is connected also to the detectors DB in the phase B street 15, FIGURES 3, 4, 5.

The purpose of terminal 29 is to stimulate a vehicle call on phase B so that the intersection controller will provide a phase B right of way interval so that a pedestrian sequence can be initiated parallel thereto. In FIGURE 6 it is evident that terminal 29 is energized with L1 power when detector relay contacts CR3-3 are closed upon push-button actuation. The circuit includes L1 line 40, lead 45, contacts CR1-2C, leads 44, 46, contacts CR5-2, lead 47, now-closed contacts CR3-3, leads 48, 49, and terminal 29.

The phase detector terminal 29 serves an additional purpose. When the intersection controller has advanced to the phase B right of way interval it is kept there by the continuous call placed on its phase B detector relay through contacts CR6-1. During the phase B right of way interval, relay coil CR6-C is energized from the phase B green signals; contacts CR6-1 are transferred to supply L1 power to terminal 29 continuously. This puts a continuous call on phase B of the intersection controller to keep the right of way signals with phase B until the clearance interval has timed out. The phase B "maximum" timer in the intersection controller must be set for at least as long as the total of the walk and clearance intervals.

CHECK CIRCUIT

The purpose of the check circuit is to prevent the pedestrian unit from starting its sequence even though the intersection controller is in the compatible right of way interval if a vehicle actuation has occurred on the opposite phase. The check circuit terminal 32 is energized with L1 power whenever the detector relay on the opposite phase is energized. The check relay coil CR2-C is thus energized if the detector relay within the intersection controller is energized. Contacts CR2-1 open and break one-half of the parallel circuit to step switch coil CR1-C. Since the phase B green terminal 34 is energized, relay coil CR5-C is energized and contacts CR5-3 are open, thus breaking the other half of the parallel circuit to stop switch coil CR1-C. The auxiliary unit therefore cannot be started out of the reset interval until the phase B green terminal is deenergized and contacts CR5-3 closed. When the phase B green terminal is deenergized the auxiliary unit will be able to move to the first portion of the walk interval without the walk light illuminated and remain there until the phase B green terminal 34 is again energized. This does not occur until the intersection controller has answered the vehicle call on the opposite phase A and then returned to the compatible phase B.

AUXILIARY TERMINAL 33

L1 power is supplied to auxiliary terminal 33 during the walk interval to be used with a delayed green timer unit.

PHASE GREEN TERMINAL

A line from the phase B green signal terminal in the intersection controller is connected to terminal 34 in the auxiliary unit. During the compatible traffic movement, L2 power is fed in on terminal 34, energizing transfer relay coil CR5-C each traffic cycle. The load relay coil CR4-C is energized therefrom during the walk interval if a pedestrian actuation has occurred. Transfer relay coil CR6-C is also energized therefrom during the walk and guaranteed clearance intervals of the pedestrian phase.

The load relay coil CR4-C is connected to be energized from the compatible vehicle right of way signal to insure safe operation. It is thus impossible to illuminate the WALK signal until the compatible vehicular movement is initiated after cross traffic has been stopped. Timing of the walk interval is likewise not started until cross traffic is halted and compatible traffic is given the right of way. This is a safety feature.

AUXILIARY TERMINAL 35

This terminal is energized with L1 power only during the walk and clearance intervals. It may be used for various auxiliary control functions external to the pedestrian unit. For example, it may cause an external relay to be energized in parallel with transfer relay CR6. It may be used to extinguish conflicting turn signal indications during the walk and clearance intervals to permit safer pedestrian crossing.

PHASE DENSITY DETECTOR TERMINAL

This terminal is normally deenergized and is closed to L1 power when a pedestrian actuation occurs. The closure is momentary if the intersection controller is in the conflicting phase. The pulse serves to call a density type intersection controller to the compatible phase. Contacts CR1-3C transfer as soon as the step switch CR1 is energized and deenergized and thus deenergize terminal 36.

The terminal 36 is not pulsed at all if the intersection controller is already in the compatible phase because contacts CR5-4 are then open.

The density type of controller to which the density yield terminal 28 connects is shown for example in United States Patent Numbers Re. 21,377, 2,265,991, 2,199,571, 2,090,619 and 2,044,907.

AUXILIARY TERMINALS 37, 38, 39

These terminals are transferred when relay coil CR6-C is energized. This occurs when the phase B green terminal 34 is energized after the auxiliary unit is in the first portion of the walk interval. The contacts serving the auxiliary terminals 37, 38, 39 are heavy duty and may be used to control traffic signals. For example, terminals 37, 38 may be connected in a circuit supplying power to left or right turn arrow signals which may be deenergized during the walk and clearance intervals to prevent vehicles from turning into the pedestrian crosswalk. Terminals 38, 39 may be connected into a circuit which flashes the DON'T WALK signal during the guaranteed clearance interval to draw the pedestrian's attention.

This completes the description of the circuit shown in FIGURE 6. It is understood that one skilled in the art may make various changes in the circuit without altering its function. It is also understood that the circuit may be applied to control different apparatus through different operations without departing from the spirit of the invention.

What is believed to be new is the invention of an auxiliary electronic timer unit capable of being interconnected with a multiphase, traffic actuated, intersection controller for the purpose of controlling an additional phase through two or more timed intervals. The form of the invention shown herein is described in relation to a pedestrian sequence. The unit is equally adapted to

use as a minor traffic movement controller or as a delayed green and clearing interval timer.

What I desire to protect by Letters Patent is described in the appended claims.

I claim:

An electronic pedestrian interval timer comprising a three bank step switch operable through a reset interval, a walk interval, and a clearance interval, a pedestrian actuatable detector, a detector relay connected to be energized by said detector and operable to close a memory circuit and to energize said step switch out of said reset interval, a first interrupter contact on said step switch operable to deenergize said step switch, said step switch thereby stepped into a first portion of said walk interval, a timing circuit comprised of a triode gas filled tube having a plate circuit, a cathode circuit, and a grid circuit, an RC timing circuit connected in said grid circuit and adapted to be charged during said reset interval and recharged between said walk interval and said clearance interval and having a first timing circuit connected thereto during said walk interval and a second timing circuit connected thereto during said clearance interval, a load relay connected to be energized during a compatible traffic movement, said load relay when energized adapted to energize a pedestrian walk signal and to connect said first timing circuit to said RC timing circuit, a plate circuit relay connected in said plate circuit and energized therefrom when said RC timing circuit can no longer prevent said gas filled triode from firing, contacts on said plate circuit relay connected to energize said step switch relay out of said walk interval, said interrupter contacts on said step switch operable to deenergize said step switch, said step switch thereby stepped into said clearance in-

terval, contacts on said step switch operable during said clearance interval to deenergize said load relay, said load relay when deenergized energizing a pedestrian clearance signal and connecting said second timing circuit to said 5 RC timing circuit, said plate circuit relay energized therefrom when said RC timing circuit can no longer prevent said gas filled triode from firing, said contacts on said plate circuit relay effective to energize said step switch relay out of said clearance interval, said interrupter contacts on said step switch again deenergizing said step switch, said step switch thereby stepped into said reset interval, said circuit thereupon readied for another pedestrian actuation.
